UNITED STATES PATENT OFFICE

127,522

DESIGN FOR AN AUTOMOBILE BODY

Laurence V. McLauchlin, Detroit, Mich., assignor
to National Display Ads, Inc., Madison, Wis., a
corporation of Wisconsin

Application July 13, 1940, Serial No. 93,613

Term of patent 14 years

To all whom it may concern:

Be it known that I, Laurence V. McLauchlin, a citizen of the United States, residing at Detroit, in the county of Wayne and State of Michigan, have invented a new, original, and ornamental Design for an Automobile Body, of which the following is a specification, reference being had to the accompanying drawings, forming a part thereof.

Figure 1 is a side elevational view in perspective of the automobile body of the present invention.

Figure 2 is a rear elevational view in perspective of Figure 1.

Figure 3 is a front elevational view in perspective of Figure 1.

Figure 4 is a longitudinal sectional view in elevation of a part of the body shown in Figures 1 to 3.

Figure 5 is a transverse sectional view through the top portion of the body shown in Figures 1 to 4 and taken at a point indicated by line 5—5 of Figure 4.

The characteristic features of my automobile body design are shown in full lines in Figures 1 to 3 of the drawings.

I claim:

The ornamental design for an automobile body, substantially as shown and described.

LAURENCE V. McLAUCHLIN.
